(57) **CLAIM**

The ornamental design for a double band nasal dilator, as shown and described.

DESCRIPTION

FIG. 1 is a top plan view of a first embodiment of a double band nasal dilator showing my new design;
FIG. 2 is a perspective view thereof, showing the dilator in an in use state;

FIG. 3 is a three-quarter perspective view thereof;
FIG. 4 is a top plan view of a second embodiment of a double band nasal dilator showing my new design;
FIG. 5 is a perspective view thereof, showing the dilator in an in use state; and,

FIG. 6 is a three-quarter perspective view thereof.
The broken line showing of human facial features is directed to environment and for illustrative purposes only; the broken lines form no part of the claimed design.
